UNITED STATES PATENT OFFICE.

DANIEL G. BUTTS, OF NEW ORLEANS, LOUISIANA, ASSIGNOR TO THE IVORY GARTER COMPANY, OF NEW ORLEANS, LOUISIANA, A CORPORATION OF LOUISIANA.

GARMENT-SUPPORTER.

1,156,835.

Specification of Letters Patent.

Patented Oct. 12, 1915.

Application filed October 11, 1910. Serial No. 586,512.

To all whom it may concern:

Be it known that I, DANIEL G. BUTTS, a citizen of the United States, residing at New Orleans, in the parish of Orleans and State of Louisiana, have invented certain new and useful Improvements in Garment-Supporters; and I do hereby declare the following to be a full, clear, and exact description of the same, reference being had to the accompanying drawings, forming a part of this specification, and to the figures and letters of reference marked thereon.

This invention relates to garment supporters and more especially to that type of supporter designed for supporting hosiery, the objects of the invention being to provide a more simple and convenient device for the purpose mentioned than those now in use and a device of such character that it may be made cheaply and of materials which will last indefinitely and not have a destructive influence one upon the other.

The invention consists in certain novel details of construction and combinations and arrangements of parts, all as will now be described and pointed out particularly in the appended claims.

Referring to the accompanying drawings; Figure 1 is a perspective view of a supporter embodying the present improvements. Fig. 2 is a side elevation of the clasp with its supporting member and the coupling plate and hook. Fig. 3 is an elevation of the friction buckle. Figs. 4, 5, 6, and 7 are similar views of the coupling plate, hook, clasp-base, and clasp plate, respectively.

Similar letters of reference in the several figures indicate the same parts.

The type of supporter illustrated in the accompanying drawings embodies, generally speaking, a limb encircling web A, of usual construction and material, one end of the web having attached thereto a hook B while the opposite end is doubled upon itself and secured to a friction slide buckle C. The loop formed by the doubled end of the web embraces and is itself included within a slot d in a coupling plate D, said slot d being centrally widened as at d' for the reception of the end of the hook B as will be readily understood from Fig. 1.

Immediately below and preferably central of the bottom of the coupling plate, an aperture d² is formed for the reception or pas-

sage of a pendant supporting member E which member is in the form of an elastic cord, the elasticity being secured by the use of vulcanized rubber. The supporting member E at its lower end, or ends, carries the garment clasp or hose engaging clasp which latter, in accordance with the present invention, is made in two parts, one part being a clasp base and the other a clasp plate constructed as follows. The clasp base which is an integral piece of material of the character to be presently referred to, embodies a central or body portion F and upper and lower offset ends F' and F², respectively. The two ends F' and F² are offset toward the front of the clasp and the intermediate or bent portions f' and f² preferably extend diagonally or at an inclination with respect to the body F as best shown in Fig. 2 of the drawings. Viewed from the front as in Fig. 6, the lower portion of the clasp base is tapered downwardly and the end rounded and smoothed to prevent tearing the garment which is engaged thereby. In the upper portion of the clasp base there are formed two apertures, one aperture G being in the offset end F' and the other aperture G' being in the bent portion f' and said apertures are adapted for the passage of one end of the supporting member E and for the attachment of the opposite end of said supporting member where the parts are assembled in the manner shown in Figs. 1 and 2.

The clasp plate H is a relatively small and preferably substantially rectangular flat plate having near its lower end an aperture h for the reception of the offset end F² of the base, said aperture H being of sufficient width and size to permit the portion f² of the base and a garment which may surround that portion to pass into the aperture as shown in Fig. 2. The upper portion of the clasp plate is provided with an aperture h' for the attachment of the end of the supporting member E and it will be particularly noted that the dimensions of the plate are such that when the parts are in garment engaging position as in Figs. 1 and 2, the upper end or edge of the plate is below the upper offset end of the base and preferably below the lower aperture in said base.

In supporters of this character which are

adapted to be worn in close contact with the person it has been found that the vulcanized rubber elastic quickly deteriorates, particularly at the points where it is in proximity to or in contact with metal members or members which are influenced by the moisture and sulfur used for vulcanizing the rubber. Under such conditions the oxidation of the metal quickly causes a deterioration of the rubber with the result that the life of the article is materially shortened. In order to overcome this serious defect and greatly prolong the life of the supporter, the clasp and the coupling plate with which the elastic comes in contact are both made of a substance which is neutral in its effect on the rubber under oxidizing conditions and said parts are preferably made of substantially transparent celluloid, thus not only obtaining the advantages referred to but giving to the supporter a unique and attractive appearance. Furthermore, this substance lends itself readily to coloring and may be made to match under-garments of various styles.

Owing to the construction of the clasp with the lower offset end of the base projected downwardly and the upper end of the plate lying below the aperture through which the supporting members pass to engage said plate, the supporting member causes the plate to act with a lever effect to pinch the bight of garment which passes around the offset end, and furthermore with this construction the clasp will remain firmly attached to the garment even though the tension on the supporting member be relieved as, for instance, when the supporter is removed from the limb by detaching the hook from the coupling plate. Furthermore, by offsetting the upper end of the base not only is said end brought out over the plate but the supporting member is held away from the person somewhat by the body of the base and the whole structure is made flat and thin so as to present no projections for catching overlying or underlying garments.

Having thus described my invention,

what I claim as new and desire to secure by Letters Patent of the United States, is—

1. In a garment supporter, the combination with a supporting member of elastic vulcanized rubber, of connecting and clasp members to which the elastic vulcanized rubber supporting member is connected formed of celluloid neutral under oxidizing conditions in its effect on the vulcanized rubber supporting member whereby the life of the rubber is prolonged. 60

2. In a garment supporter, the combination with a pliant supporting member having elastic vulcanized rubber incorporated therein, of a garment engaging clasp depending therefrom formed of non-metallic 65 substance neutral in its effect on vulcanized rubber and embodying a clasp base having its upper and lower ends offset from the plane of the body and an aperture in its upper end for the reception of the pliant member and a clasp plate having an aperture therein for the reception of the lower off-set end of the base and a second aperture for the reception of the pliant member, the upper edge of the plate lying below the 75 upper offset end of the base when the parts are in garment engaging position.

3. In a garment supporter, the combination with a pliant supporting member, of a garment engaging clasp depending therefrom and embodying a clasp base formed of celluloid having an aperture at the upper end for the passage of the pliant member and having its lower end offset and extended downwardly and a flat clasp plate formed 85 of celluloid having an aperture therein for the reception of the offset portion of the base and an aperture near the top for the reception of the pliant member, the upper end of the plate being below the upper end 90 of the base and the lower end of the plate confined behind the offset end of the base when the parts are in garment engaging position.

DANIEL G. BUTTS.
